UNITED STATES PATENT OFFICE.

CHADBOURNE MELCHER WHITMORE, OF SUPERIOR, WISCONSIN.

COUNTERBALANCE FOR PEDALS.

SPECIFICATION forming part of Letters Patent No. 669,569, dated March 12, 1901.

Application filed September 14, 1899. Serial No. 730,480. (No model.)

To all whom it may concern:

Be it known that I, CHADBOURNE MELCHER WHITMORE, a citizen of the United States, residing at Superior, in the county of Douglas and State of Wisconsin, have invented certain new and useful Improvements in Counterbalances for Pedals; and I do hereby declare the following to be a full, clear, and exact description of the invention, such as will enable others skilled in the art to which it appertains to make and use the same.

My invention relates to improvements in weights or counterbalances for pedals, and particularly for bicycle-pedals.

15 It consists in a weight provided with one or more elastic bands adapted to engage a pedal, so as to suspend the said weight at a suitable point beneath the same to hold the pedal normally in a desired position.

20 It also consists of certain other novel constructions, combinations, and arrangements of parts, as will be hereinafter more fully described and claimed.

In the accompanying drawings, Figure 1 25 represents a longitudinal section through a counterbalance constructed in accordance with my invention, showing the manner of supplying the elastic supports. Fig. 2 represents a transverse vertical section through 30 the said counterbalance and a bicycle-pedal, showing the manner of securing the said counterbalance in place. Fig. 3 represents a detail sectional view of the said counterbalance, it being formed in a slightly different 35 manner. Fig. 4 is an end elevation of a still different form of counterbalance, and Fig. 5 is a side elevation of the same.

40 My invention is designed to supply a compact, simple, and adjustable counterbalance for bicycle-pedals and one which can be quickly and easily adjusted to hold the pedal normally in a desired position, whether the said pedal be provided with a toe-clip or not.

45 For carrying out the features of my invention I preferably form a counterbalance of a folded piece of metal, as 1, the said weight being so folded as to form a centrally and downwardly projecting loop or fold, as 2, and outwardly-bent side portions, as 3 3, forming 50 upper loops, as at 4 4. In order to attach this weight to a pedal, one or more elastic bands of cord, as 5 5, are passed between the

outer side portions 3 3 and the center fold, so as to pass through the upper loops 4 4, as clearly seen in Figs. 1 and 2 of the drawings, 55 the elastic being so arranged as to form pedal-engaging loops, as 6 6, which may be stretched upwardly over the foot-engaging portions 7 7. The elastic 6 6 may be so drawn over the edges of the pedal with respect to the counterbalance that the said counterbalance will hang directly beneath the axis of the pedal, as seen in Fig. 2, or at a suitable distance upon either side of the said axis to properly balance the pedal. This adjustment of the 60 counterbalance forms an important feature of my invention, especially when toe-clips are applied to the pedals. A counterbalance of this kind can be so adjusted as to exactly 65 counterbalance the weight of the toe-clip and 70 hold the pedal horizontal.

As seen in Fig. 3 of the drawings, the outer side folded portions of the counterbalance may be quite small, if desired, as at 8 8, without departing from the spirit of my invention. It will also be apparent that other 75 portions of the attachment of said elastic supports or bands to the counterbalance may be employed, if desired.

As shown in Figs. 4 and 5, the counterbalance may be made of a flat material, as 13, folded downwardly at the sides and inwardly and upwardly at the center, as at 14, the upwardly-extending ends being adjacent to the top cross portion. This manner of folding 80 the material forms two recesses, as 15 15, for receiving the supporting-elastic. The elastics are preferably arranged in the said recesses so as to cross each other, similar to the way the elastics are arranged in Fig. 1. 90

From the above description it will be apparent that my improved counterbalance is exceedingly simple in its construction and that it can be readily adjusted to hold the pedal horizontally and in proper position to 95 receive the foot of the rider, whether the said pedal be provided with a toe-clip or not.

Having now described my invention, what I claim as new, and desire to secure by Letters Patent, is—

1. A counterbalance for pedals, comprising a weight, an elastic cord formed with loops to engage a pedal, the said cord being entwined through and about the said weight so as to

automatically hold the weight at different points to which it may be slipped on said elastic cord between the said loops, whereby the weight will be held at a proper point beneath the pedal to balance it, substantially as described.

2. A counterbalance for pedals, comprising a weight formed of folded metal, an elastic cord for supporting said metal upon a pedal, the said cord being twisted twice and arranged within the folds of the weight so that a part of the weight is included between said

twisted portions, end loops formed in said cord for engaging the pedal, the arrangement being such that the weight may slip 15 back and forth between the twisted portions of the elastic cord to adjust it to different points with respect to the axis of the pedal.

In testimony whereof I hereunto affix my signature in presence of two witnesses.

CHADBOURNE MELCHER WHITMORE.
